WINDOW REGULATOR

John H. Roethel, Detroit, Mich., assignor to Automobile Ventilation, Inc., Detroit, Mich., a corporation of Michigan

Application September 25, 1933, Serial No. 690,869

11 Claims. (Cl. 268—126)

5 My invention relates to window regulators particularly adapted for use in vehicle bodies where-
in the windows are mounted for horizontal as well as vertical sliding movement, such windows being hereinafter referred to as two-direction sliding windows.

10 It is an object of my invention to provide a window regulator for use with two-direction sliding windows having improved means for positively shifting the window vertically and also horizontally in the plane of the window when the latter is in predetermined elevated position.

15 It is a further object of my present invention to provide a window regulator which is inexpensive to manufacture, easy to install and particularly adapted for use in the production assemblies of windows and regulators as, for example, in the construction of windows in motor vehicle bodies.

20 Other objects of this invention will appear in the following description and appended claims, reference being had to the accompanying drawings forming a part of this specification wherein like reference characters designate corresponding parts in the several views.

25 Fig. 1 is a fragmentary side elevation with parts broken away of a door of a motor vehicle body showing a window regulator embodying my invention installed therein showing the window glass in the closed position.

30 Fig. 2 is a view similar to Fig. 1 but showing the window glass and the parts of the regulator embodying my invention in the position for providing a vent opening between the forward edge 35 of the glass and the front door pillar.

Fig. 3 is a similar view to Fig. 2 but showing a modification of the window regulator embodying my invention.

35 Fig. 3A is a detail section taken on lines 3—3 of Fig. 3.

Fig. 4 is a view similar to Fig. 1 showing a modified form of window regulator embodying my invention.

40 Fig. 5 is a sectional view taken on the line 5—5 in the direction of the arrows of Fig. 2.

Fig. 6 is a sectional view taken on the line 6—6 in the direction of the arrows of Fig. 2.

45 Fig. 7 is a fragmentary elevation showing another modification of my invention.

50 Before explaining in detail the present invention it is to be understood that the invention is not limited in its application to the details of construction and arrangement of parts illustrated in the accompanying drawings, since the invention is capable of other embodiments and of be-

ing practiced or carried out in various ways. Also it is to be understood that the phraseology or terminology employed herein is for the purpose of description and not of limitation, and it is not intended to limit the invention claimed herein 5 beyond the requirements of the prior art.

There is shown in the drawings an automobile door 20 having a front pillar 21 in which is placed a glass runway channel 22. The door 20 is provided with a rear pillar 23 having a deep glass 10 runway channel 24 terminating at the window sill and thence provided with a shallow channel 24a extending below the window sill. A window glass 25 is provided and is adapted for slidable movement vertically in the channels 22, 24 and 15 24a, and horizontally into the deep channel 24. A channel-shaped retainer strip 26 is secured to the bottom of the glass 25. As shown in Figs. 3 and 4, the window regulator mechanism 27 may be installed at any suitable place in the door 20, 20 such for example as on the lock board, and is provided with a fixed supporting plate 30. Rotatably mounted on the supporting plate 30 are meshed gears 31 and 32. A rotatable handle 33 is provided to actuate the regulator mechanism 25 27 and is suitably attached to a driving pinion 34 meshed with a gear sector preferably punched from the same metal blank as the gear 32. In the present embodiments of the invention the window regulator is shown by way of example 30 as of the two arm type and comprises a pair of swinging arms 37 and 40 for raising and lowering the window, these arms carrying at their outer ends button devices or headed studs 42 and 43, respectively, which slide longitudinally in 35 channel ways formed in the retainer strip 26. The arm 40 also is provided with a lateral cam extension 41 constructed for the purpose of shifting the window horizontally and locking the window when the latter is in predetermined ele- 40 vated position.

In one embodiment of my invention as shown in Figs. 3 and 4, the cam extension 41 is provided with a cam slot 44 and an extending finger 45. A plate 46 depends from the channel retainer 45 26 and is provided with a pin or stud 47 which is secured thereto at a position where it may be engaged in the slot 44. A curved cam surface 50 is formed on the extension 41 between the slot 44 and the stud 43.

55 In the embodiment of my invention shown in Figs. 1 and 2 the cam extension 41 is provided with an extending side or cam forming edge 51 adapted to engage the side of the pin 47 for retracting the glass. In this embodiment of my 55

invention the contact of the cam edge 51 with the pin 47 is employed for the shifting of the glass 25 in one horizontal direction, whereas in the embodiment of my invention shown in Figs. 3 and 4 the opposite edges of the slot 44 engage successively the pin 47 to shift the window 25 in a forward as well as a rearward horizontal direction.

In the embodiment of my invention shown in Fig. 7 the cam 41 carries a pin or stud 53 which contacts successively with cam edges or surfaces 54a and 54b formed on a plate 54 secured to the glass retainer 26.

The glass retainer 26 as shown in Fig. 6 is provided with a U-shaped glass receiving channel 55 forming the upper side of a runway 56 and having felt or similar glass engaging cushioning elements 57 secured therein. Secured to the U-shaped glass receiving channel 55 is a member 58 forming the back and bottom portion of the runway. As here shown the runway 56 has a constricted front opening extending longitudinally of the channel 26 which is of less height than the diameter of the studs 42 and 43 thereby interlocking the latter against withdrawal during their normal sliding movement within the runway 56. The member 58 is provided with a lower extending lip 59 which, as hereinafter described, provides a bearing portion. The member 58 may have a cut-away notched portion in the bottom thereof, as shown at 60 in Fig. 3, providing an opening through which the enlarged heads of the studs 42 and 43 are inserted vertically into the runway 56. A variation of this construction is shown in Figs. 1, 2 and 6, wherein instead of the cut-away opening 60 the extending lip 59 is pressed to provide depressed notch portions 61 and 62 which are adapted to permit the installation of the heads of the studs 42 and 43 through the face of the member 58 in order to occupy their operative positions within the runway 56. In this embodiment of my invention the back wall of member 58 is punched inwardly to provide a lug 63 which extends into the runway 56 and is contacted by the stud 43 to shift the window glass 25 horizontally in one direction.

The studs 42 and 43 as shown in Figs. 5 and 6, are each provided with an enlarged head 64 and a restricted neck 65, and are secured to the respective arms 37 or 40 by riveting or other suitable means. Mounted on the restricted neck portion 65 of each stud is a conical washer 66 which is yieldingly held in position by a spring 67. The conical washer engages correspondingly shaped flared bearing surfaces formed by the lip 59 and the outer lower side of the channel strip 55.

In the operation of the several embodiments it will be seen that the window glass 25 will be raised and lowered in a vertical direction as a result of the swinging movement of the regulator arms 37 and 40, these arms swinging toward and from each other in conventional manner and being operated by the gearing from the usual 65 crank handle 33. During this operation the headed studs or buttons 42 and 43 travel longitudinally in the runways 56 and due to the constricted front opening of these runways the studs will be interlocked against horizontal withdrawal.

In the operation of the embodiment shown in Figs. 1 and 2 it will be seen that when the window glass approaches its full elevated position the cam face 50 on the swinging arm 41 will travel against the stud or pin 47. Due to the fact that this cam face is formed on a curve concen-

tric with the axis of swinging of arm 41 it will simply contact with the pin thus providing a supporting medium so that at this time the window will have a three-point support. At the same time the cam 50 while in engagement with pin 47 will lock the window glass against rearward sliding movement into the deep channel. Hence, as the window glass moves into elevated position opposite the deep channel 24, at which time its rear vertical edge will be unsupported, the window will be maintained against tilting movement and also against rearward sliding movement by virtue of the three-point support formed by studs 42 and 43 and cam 50 contacting with pin 47. When the window glass reaches its full elevated position the pin 47 moves into engagement with the upper end of cam face 51 and continued swinging movement of arm 41 will result in shifting the glass rearwardly into the deep channel by virtue of the engagement of stud 43 with the lug 63. During this operation pin 47 travels along the edge of cam 51 so that the window glass will be locked in any horizontally moved position except when the regulator arms are swung. It will be seen from Fig. 2 that when the arms are swung in the opposite direction the cam 51 will engage pin 47 and shift the window horizontally into closed position, and upon continued downward swinging movement of the arms the window will then be lowered.

The operation of the embodiment shown in Fig. 7 substantially corresponds to that above described since in this instance certain of the operating parts are simply reversed. That is to say, the cam surface 54a, which is concentric with the axis of swinging of the arm 40, cooperates with the pin 53 and performs therewith the same function as the cam 50 and pin 47 of the previous embodiment. Moreover, the cam surface 54b in cooperation with the pin 53 performs the same function as the cam 51 and pin 47 in effecting a horizontal retraction of the window in its upper closed position.

In each of the preceding embodiments it will be seen that the notched portions 61 and 62 formed in the lower horizontal flanges of the runways provide openings of sufficient diameter to permit direct and simultaneous insertion of the button devices 42 and 43 into the runways when the window glass is being assembled with the regulator arms.

Referring to the embodiment illustrated in Figs. 3 and 4, in this instance as the regulator arm 40 is swung upwardly to move the glass vertically into closed position, the cam 50 will travel into contact with the pin 47 thus supporting the window glass and locking it against horizontal displacement into the deep channel, as in the previous embodiments. In this instance the opposite edges of the cam slot 44 provide the means for successively shifting the window horizontally in opposite directions, the forward edge of the cam slot performing the same function in moving the window into ventilating position as the lug 63 and stud 43 in the previous embodiment and the rear edge of the cam slot performing the same function as the cam 51 or 54b.

In assembling the regulator arms with the retainer strip 26 in the embodiment of Figs. 3 and 4, the arms are first moved into extreme upright positions whereby the studs 42 and 43 underlie the cut-away opening 60 in the bottom of the runway. The window glass is then shifted downwardly and vertically until the studs lie opposite the inner ends of the runways and then the

regulator arms are cranked so as to swing the arms apart and shift the studs horizontally into the runways. Since it is necessary during this operation to install the pin 47 in the cam slot 44, the outer edge of the extension 41 is formed with an embossed cam portion 41a, see Fig. 3A. Thus, as the arm 40 is swung to the left in order to project the stud 43 into the runway, at the same time the inclined cam portion 41a will ride up over the end of pin 47 springing the cam extension 41 outwardly sufficiently to permit travel of the pin 47 into the cam slot 44.

In the foregoing embodiment means is provided for limiting the downward movement of the window glass at its lowest position. This is accomplished in Figs. 3 and 4 by means of a projecting stop 80 on gear 31 which, as the arms swing downwardly to the lowest position, engages the lower edge of the plate 30 and prevents further movement of the window into the door well. If desired the lower limit of movement of the window glass may be determined by means of rubber bumpers 81 and 82 mounted in the lower ends of the glass runways and in position to be engaged by the glass.

I claim:

1. A regulator for a window mounted for vertical sliding movement and for horizontal movement in the plane of the window when the latter is in elevated position, comprising a retainer member adapted to be secured to the lower edge of a window and having a longitudinal horizontal runway, said regulator including a swinging arm having a projecting device slidable in said runway for raising and lowering the window, said retainer member having a stop integrally formed from said member, and projecting into said runway into the path of said device and adapted to be engaged by said device when the window is in elevated position for sliding the window horizontally.

2. A regulator for a window mounted for vertical sliding movement and for horizontal movement in the plane of the window when the latter is in elevated position, comprising a retainer member adapted to be secured to the lower edge of a window and having a longitudinal horizontal runway, said regulator including a swinging arm having a projecting device slidable in said runway for raising and lowering the window, said retainer member having a stop struck out from the metal of said member, and projecting into said runway into the path of said device and adapted to be engaged by said device when the window is in fully elevated position for sliding the window horizontally.

3. A regulator for a window mounted for vertical sliding movement and for horizontal movement in its plane when the window is in predetermined elevated position, including a retainer member adapted to be secured to the lower edge of a window and having a longitudinal horizontal guideway therein, a depending extension carried by said member, said regulator also including a swinging arm having a projecting device slidably received in said guideway for raising and lowering the window, said retainer member having a stop formed from the metal thereof and projecting into the path of said device and adapted to be engaged thereby for shifting the window horizontally, and means carried by said arm separate from said device and adapted to engage said extension for shifting the window horizontally in the opposite direction.

4. A regulator for a window mounted for ver-

tical sliding movement and for horizontal movement in its plane when the window is in predetermined elevated position, a retainer member adapted to be secured to the lower edge of a window and having a longitudinal horizontal guideway, a depending extension carried by said member, said regulator including a swinging arm having a projecting device slidably received in said guideway for raising and lowering the window, said retainer member having a stop formed from the metal thereof and projecting into the path of said device and adapted to be engaged thereby for shifting the window horizontally, means carried by said arm separate from said device and adapted to engage said extension for shifting the window horizontally in the opposite direction, and cooperating cam means carried by said arm and extension for locking the window against horizontal movement at a predetermined elevated position of the window.

5. In a regulator mechanism for a window mounted for vertical and horizontal sliding movement, a retainer member secured to the lower edge of the window and having a longitudinal runway, a regulator including a swinging arm having a device slidable in said runway for raising and lowering the window, a stop in said runway engageable by said device for shifting the window horizontally in one direction, and an extension carried by said arm and having means cooperating with said retainer member for shifting the window horizontally in the opposite direction.

6. In a regulator mechanism for a window mounted for vertical and horizontal sliding movement, a retainer member secured to the lower edge of the window and having a longitudinal runway, a regulator including a swinging arm having a device slidable in said runway for raising and lowering the window, a stop in said runway engageable by said device for shifting the window horizontally in one direction, and an extension carried by said arm and having means cooperating with said retainer member for shifting the window horizontally in the opposite direction, said extension also having means for locking said window against horizontal movement when in predetermined elevated position.

7. In a regulator mechanism for a window mounted for vertical and horizontal sliding movement, a retainer member secured to the lower edge of the window and having a longitudinal runway, a regulator including a swinging arm having a device slidable in said runway for raising and lowering the window, a stop in said runway engageable by said device for shifting the window horizontally in one direction, a depending extension on said retainer member and an angular extension on said arm, said extensions having separate cooperating means for successively shifting the window horizontally in the opposite direction and for locking the window against horizontal movement when in predetermined elevated position.

8. A window regulator comprising a pair of swinging arms, a retainer channel secured to the lower edge of a window and having an open runway extending longitudinally thereof, studs secured to said arms and extending into said runway, said runway having an opening or openings thereinto adapted to permit the installation of said studs, and a lug on one side of said channel and projecting into said runway for contact by one of said studs for shifting the window in its horizontal plane.

9. A window regulator adapted to impart vertical and horizontal sliding movement to a window and including a fixed supporting plate, swinging arms pivotally mounted thereon, means for swinging said arms, a retaining channel provided with a longitudinal guideway and adapted for mounting on the lower edge of the window, studs secured to said swinging arms and extending in said runway, means integral with said runway and adapted for contact with one of said studs to slide the window in its horizontal plane in one direction, a depending member secured to said channel, a member secured to one of said arms and adapted to contact said depending member to slide the window in its horizontal plane in an opposite direction and to lock the window against movement in its horizontal plane while moving in a vertical direction.
10. In a regulator mechanism for a window mounted for vertical sliding movement and also for horizontal movement in its plane when the window is in predetermined elevated position, comprising a retainer member adapted to be secured to the lower edge of the window and having a longitudinal guideway, regulator mechanism including a swinging arm having a device interlocked in said guideway and slidable therein

for raising and lowering the window, a stop carried by said retainer member and engageable by said device for shifting the window in its plane horizontally in one direction, and separate means carried by said arm and cooperating with said retainer member for shifting the window horizontally in the opposite direction.

11. In a regulator mechanism for a window mounted for vertical and horizontal sliding movement, a retainer member secured to the lower edge of the window and having a longitudinal runway, a regulator including a stationary supporting plate, swinging arms having devices slidably in said runway for raising and lowering the window, a stop in said runway engageable by one of said devices for shifting the window horizontally in one direction, means carried by one of said arms cooperating with said retainer member for shifting the window horizontally in the opposite direction, meshed gears secured to said arms for swinging the same, driving mechanism for operating said gears, and a stop attached to one of said meshed gears and adapted to engage said supporting plate to limit the downward swinging movement of said arms.
